(57) **CLAIM**

The ornamental design for a V-shaped four bicycle carrier, as shown and described.

DESCRIPTION

FIG. 1 is an elevated angled view of the V-shaped four bicycle carrier.

FIG. 2 is an exploded view of the V-shaped four bicycle carrier components.

FIG. 3 is a front view of the V-shaped four bicycle carrier with a bicycle attached thereto.

FIG. 4 is a back side view of the V-shaped four bicycle carrier.

FIG. 5 is a front side view of the V-shaped four bicycle carrier.

FIG. 6 is a side view of the V-shaped four bicycle carrier.

FIG. 7 is a top view of the V-shaped four bicycle carrier; and, FIG. 8 is a bottom side view of the V-shaped four bicycle carrier.

The broken lines illustrate unclaimed environmental structure.

1 Claim, 8 Drawing Sheets

Matter enclosed in heavy brackets [ ] appears in the original patent but forms no part of this reissue; matter printed in italics indicates the additions made by reissue.
